United States Patent Office

Des. 215,639
Patented Oct. 14, 1969

215,639

PILLOWCASE OR SIMILAR ARTICLE OF BED LINEN

Edward C. Taiman, Tarrytown, N.Y., assignor to Cannon Mills Company, Kannapolis, N.C., a corporation of North Carolina

Filed Sept. 20, 1968, Ser. No. 13,651

Term of patent 14 years

Int. Cl. D6—09

U.S. Cl. D92—26

The figure is a plan view of a pillowcase showing my new design, the side opposite thereto being substantially identical.

I claim:

The ornamental design for a pillowcase or similar article of bed linen, substantially as shown and described.
